UNITED STATES PATENT OFFICE.

JOHN R. PADESKY, OF LA CROSSE, WISCONSIN, ASSIGNOR TO NATIONAL GAUGE & EQUIPMENT COMPANY, OF LA CROSSE, WISCONSIN, A CORPORATION OF WISCONSIN.

CAP FOR RADIATORS.

Application filed July 31, 1925. Serial No. 47,290.

This invention relates to an emblem cap device for the top of a radiator for automobiles and similar articles.

The purpose of the invention is to so arrange the emblem cap that it will be retained upon the radiator in the proper position to make the emblem appear most prominently and suitably. In the use of emblem devices trouble has been experienced in maintaining the emblem in the proper position to make it effective for the purpose intended and this has been due in part to the fact that the screw threads of the cap and the neck of the radiator become worn and therefore the emblem, when screwed tightly upon the neck of the radiator, does not lie in proper position to give the attractive effect intended; for it is often out of line with the front of the radiator. Moreover, after the threads become worn the vibration of the vehicle will cause the emblem cap to be turned out of perfect alignment with the front of the radiator, so as to impair its attractiveness. This improvement is adapted to make the emblem cap fit properly on the neck of the radiator and whenever the cap is turned to the proper position it will then be held in that position by a contact between the cap and the neck of the radiator.

Referring to the drawings:

Fig. 1 is a front view showing the cap, radiator neck and associated parts in section.

Fig. 2 is a sectional view on the lines 2-2 of Fig. 1.

Fig. 3 is a side view of the cap with the emblem secured thereto.

Referring to Fig. 1, the emblem is designated by 1 and this emblem is secured to the top of the cap 2 in the manner shown. The interior of the cap is screw threaded at 3 in the usual manner as indicated in Figs. 1 and 2 and the neck of the radiator 4 has the usual external screw threads as indicated in 5. The interior of the cap is formed with an annular recess or seat 6 and with an annular shoulder 7. A coil spring 8 is placed within the cap and confined between the seat 6 and a circular plate 9, which plate is held within the interior of the cap by the head of a screw 10 with the threaded end of the screw 10 screwed into the top of the emblem cap, as indicated in Figs. 1 and 2. The parts are so adjusted

that in the normal position of the plate 9, and by that is meant the position it assumes when the cap is removed from the neck of the radiator, the plate will be in its extreme outer position wherein it will bear against and be confined by the head 11 of the screw 10 and in this position the coil spring has a minimum amount of tension. It is apparent that in that position of the plate the cap can be secured to the neck of the radiator by turning of same in the usual way. The emblem cap can then be turned further on the neck of the radiator until the parts assume the position shown in Fig. 1, when sufficient spring tension will be exerted upon the plate 9 to cause the requisite amount of friction to be exerted between the plate and upper end of the neck to hold this cap securely against turning on the neck of the radiator. The shoulder 7 formed on the interior of the emblem cap will act as a stop to limit the rotary movement of the cap upon the neck of the radiator, and at the end of this extreme movement the plate 9 will be forced against the said shoulder, but it is apparent that for all ordinary uses the emblem cap will never be turned to bring the plate in engagement with that shoulder. As soon as the plate contacts the upper end of the radiator neck, further turning of the cap places the spring under increasing tension.

Having thus described my invention, I claim:

The combination of a radiator neck externally threaded with a cap threaded internally, the threaded portions permitting the cap to be turned sufficiently to bring the cap into rigid engagement with the neck at the end of the turning movement, a spring and disk placed within the cap, means for slidably mounting the disk with said spring between the neck and cap, the spring being of such tension as to permit the cap to be given its full turning movement for rigidly securing the cap to the neck, but contracting automatically a predetermined amount at each turn of the cap, whereby said spring will hold the cap securely against reverse turning movement in any position the cap will assume just prior to its complete turning movement.

In testimony whereof, I have hereunto set my hand this 27th day of July, 1925.

JOHN R. PADESKY.
